UNITED STATES PATENT OFFICE.

JOHN A. KIMBERLY, JR., OF ALBANY, NEW YORK.

PAPER-ROLL HOLDER.

1,331,931.

Specification of Letters Patent. Patented Feb. 24, 1920.

Application filed October 2, 1919. Serial No. 327,915.

To all whom it may concern:

Be it known that I, JOHN A. KIMBERLY, Jr., a citizen of the United States, residing at Albany, county of Albany, State of New York, have invented a certain new and useful Improvement in Paper-Roll Holders, and declare the following to be a full, clear, and exact description of the same, such as will enable others skilled in the art to which it pertains to make and use the same, reference being had to the accompanying drawings, which form a part of this specification.

This invention relates to paper roll tension devices and its object is to provide a simple and efficient device for placing a tension on the roll to prevent over-running of the roll during unwinding of paper therefrom, and whereby the withdrawn strip is continuously held taut. A further object of the invention is a tension device that may be used without regard to the direction of rotation of the roll, operating with equal facility on rotation in either direction. A further object of the invention is to provide a tension device consisting of a stationarily held shaft on which the roll is rotatable and a tension device on the shaft engaging the inner surface of a plug or disk in the roll core, whereby certain strain is required to rotate the roll. These and other objects and the several novel features of the invention are hereinafter more fully described and claimed and the preferred form 35 of the device is shown in the accompanying drawings in which—

Figure 1 is an elevation partly in section showing a paper roll as mounted for use in a printing and serving machine, a portion 40 of the machine only being shown.

Fig. 2 is a section through the printing and serving machine showing the paper roll in elevation and supporting members therefor within the machine case.

Fig. 3 is a view of the end of the roll opposite from that shown in Fig. 1.

Fig. 4 is a section through the roller showing the shaft and mountings therefor.

Fig. 5 is a perspective view of the core. The device consists of a paper roll 1 having a hollow core 2 of cardboard or other suitable material and within one end of which is placed a plug or disk 3 secured to the core of the paper roll 1 and having an aperture therethrough for the small end 5 of the shaft as is shown more particularly in

Figs. 4 and 5. In the large part 6 of the shaft is a spring 7 extending spirally about the small end 5 of the shaft and having one end fastened to the large end 6 at 8. 60 The end 6 is provided with a rectangular end 9 which is adapted to fit within the slot 10 in the bracket 11 which is secured to the printing and serving machine case as shown more particularly in Figs. 1 and 65 2. By means of the end 9 fitting in the slot 10 in the bracket 11, the shaft is held from rotation, the end 6 being made of a size to allow rotation of the paper roll 1 thereabout. At the opposite end of the roll 1, the 70 small end 5 of the shaft extends through the plug or disk 3 and is supported in a bracket 12 which is also secured to the side of the printing and serving machine. As shown in Fig. 3 the bracket 12 is provided with an 75 angular slot 13 ending in a slot 14 in which the end 5 of the shaft seats, the slots 13 and 14 being provided to allow the roll and end 5 therein to be set in place in the bracket. The arrangement of the slots 13 and 14 provides a lug 15 which prevents displacement 80 of the roll when rotated.

In operation the shaft shown in Fig. 5, is placed within the roll in the manner shown in Fig. 4, the spring 7 being compressed between the plug or disk 3 and the end of the large part 6. When the shaft is thus forced to position against the spring 7 and then mounted in the brackets as shown the tension of the spring 7 against the plug or disk 90 3 yieldably holds the roll from rotation. The plug or disk 3 being stationarily mounted within the roll, rotates with the roll and the shaft is held from rotation by the rectangular end 9 fitting the slot 10 in 95 the bracket 11. Thus with the arrangement shown, the spring 7 tends to frictionally engage the end of the plug or disk 3. The spring being secured to the shaft is thereby held from rotation and by this engagement 100 of the spring 7 against the plug or disk 3, the paper roll is yieldably held from rotation. By drawing out the spring 7, the friction between the spring and the plug or disk 3 is increased and by forcing the spring 105 turns closer together the friction between the member 3 and the spring 7 is decreased so that by this means the resistance to rotation of the roll may be increased or decreased as the operator may desire. As 110 shown more particularly in dotted lines in Fig. 2, rolls of different widths may be used

with the same shaft provided however that the core openings in the rolls are of the same diameter. A narrow roll is shown by use of the dotted lines 16 in Fig. 2 and the dotted line 17 representing the protruding portion of the large shaft end 6. It can be seen more particularly from Fig. 4 that the spring 7 forcing against the plug or disk 3 forces the plug or disk and roll to which it is secured tightly against the bracket 12 so that the edge of the roll is always forced to position adjacent the bracket 12 by the spring 7, the width of the roll being immaterial. By using several rolls of different widths and several brackets 12 in alinement within the printing and serving machine the several sheets of different widths will always be served from the rolls in alinement on one edge. This feature is particularly desirable in instances where a narrow sheet is used for the sales slip and the wider slip being used for a copy for the manufacturer or retailer and by this use of the wider slip for the copies the manufacturer or retailer is provided with a space or margin on which to write instructions, notations, etc., pertaining to that special order. It is to be noted that the resistance to rotation is not only produced by the friction of the spring 7 on the plug or disk 3 but also on account of the roll and plug being forced against the bracket 12 by the said spring, producing a friction between the face of the bracket 12 and the plug or disk 3. This further increases the resistance of the roll to rotation and the brackets 11 and 12 are to be understood as being of sufficient solidity to prevent any spring action of the said brackets. It is to be understood that the brackets 11 and 12 need not be of the specific character described but may be changed in design to conform to that of the device with which it is used, the necessary characteristics of the roll support being that the shaft be held from rotation at one end and a support for the shaft be provided at the other end.

Without the use of a tension device the paper rolls of printing and serving machines frequently over-run causing undesirable loops in the withdrawn strip and frequently causing disarrangement of the several paper strips ordinarily used in the printing and serving machine. By the arrangement here shown such possibility is prevented.

For the foregoing description it becomes evident that the device is of a simple nature, is very efficient in operation and accomplishes the objects desired.

Having thus briefly described my invention its utility and mode of operation what I claim and desire to secure by Letters Patent of the United States is—

1. A paper roll holder for printing and serving machines and the like comprising

a non-rotatable shaft extending through the roll and on which the roll is rotatable, a spring secured to the shaft, a member fixedly supported in the paper roll against which the said spring frictionally engages, and through which the end of the shaft extends.

2. A tension device for paper rolls comprising a stationary shaft or support extending through the roll, a coiled spring secured to the shaft and extending longitudinally thereof, an apertured member fixedly secured in the said paper roll against which the said spring frictionally engages and through which the said shaft extends when in assembled relation with the roll.

3. A tension member for a paper roll having a core, comprising the combination with a non-rotatable shaft extending through the core, of a coiled spring secured to the shaft and extending spirally thereabout and an apertured member rotatable with the core against which the said spring frictionally engages and through which the said shaft extends when in assembled relation with the roll.

4. A tension member for wound rolls of material having a central core comprising in combination with a non-rotatable shaft extending through the core, a coiled spring secured to the shaft at one end and extending spirally thereabout, a member fixedly secured in one end of the core against which the said spring frictionally engages and through which the end of the said shaft extends when in assembled relation with the roll.

5. In a printing and serving machine provided with a paper roll having a central aperture, a frame, a shaft fitting the said aperture and extending therethrough, a support therefor, means on the support for holding the said shaft from rotation, the paper roll being rotatable on the shaft, a spring member secured to the shaft, a member secured in the end of the roll aperture against which the said spring frictionally engages and through which the said shaft extends when assembled in relation with the roll.

6. In a paper roll holder a non-rotatable shaft extending through the roll and on which the roll is rotatably mounted, a coiled compression spring secured thereto, a member fixed to rotate with the roll and frictionally engaged by the spring, the spring being placed under compression by the positioning of the roll on the shaft, and yieldably preventing rotation of the roll.

7. In a paper roll holder, a non-rotatable shaft extending through the roll and on which the roll is rotatably mounted, a spring secured to the shaft and placed under compression by the mounting of the roll thereon, a member fixed to rotate with the roll

and frictionally engaging the said spring whereby rotation of the roll is yieldably prevented.

8. In a printing and serving machine, a frame, notched brackets provided on the opposite sides of the frame, a shaft having one end of large diameter and one end of small diameter engaging the respective brackets, the end of large diameter engaging in its respective bracket in a manner to prevent rotation of the shaft, a coiled compression spring secured in the end of the large portion of the shaft and extending

spirally about the small portion thereof, a hollow core having a paper roll wound thereon, the hollow core being of a diameter to be freely rotatable on the shaft, an apertured member secured in the hollow core at one end against which the said spring frictionally engages and through which the small portion of the shaft extends, the positioning of the shaft in the brackets compressing the spring.

In testimony whereof, I sign this specification.

JOHN A. KIMBERLY, JR.
